LOUIS M. SPENCER, OF HIGHLAND PARK, MICHIGAN.

CABLE-HAULING AND BODY-DUMPING MECHANISM.

1,424,425.

Specification of Letters Patent. Patented Aug. 1, 1922.

Application filed August 29, 1918. Serial No. 251,907.

To all whom it may concern:

Be it known that I, LOUIS M. SPENCER, a citizen of the United States, and residing at Highland Park, in the county of Wayne 5 and State of Michigan, have invented a new and Improved Cable-Hauling and Body-Dumping Mechanism, of which the following is a specification.

In my applications for United States Letters Patent, Serial No. 137,093, filed December 15, 1916, and 176,648, filed June 25, 1917, I have shown and claimed a hydraulic hoist mounted on a truck or tractor and mechanism whereby it may be either utilized to 15 tilt a dump body located on the truck or a second dump body on a trailer, or both, at will. As shown therein, the necessary connections are made by hooking or shackling the desired cable or set of cables to the piston rod or by otherwise selectively or simultaneously placing said cables under the influence of the piston rod with which the hoist is provided.

The present invention relates particularly 25 to means whereby the different connections may be more readily made, but it may be applied in installations in which the hoist is used for purposes other than the tilting of vehicle bodies and is of application generally where it is desired to employ the expensive hoisting unit, in this instance the cylinder, piston, piston rod, pump, clutch, etc., for dual purposes. It is applicable also 30 to hoists other than of the hydraulic type, for example, to screw hoists, as will be understood later.

One feature of the invention resides in a pair of hooks or the like movable transversely of the piston rod or the equivalent 40 and adapted to be picked up by the latter to actuate either one or the other of two independent hoisting or hauling cables.

The invention further consists in a pair 45 of connecting elements symmetrically disposed with reference to a longitudinal plane through the piston rod, and means for simultaneously moving said elements into or from the path of travel of the piston rod construction to connect them to or remove 50 them from the influence thereof.

Another feature of the invention resides

in means for automatically properly positioning the connecting elements with reference to the plane about which they are intended to be symmetrical; the invention also 55 consists in means for properly positioning the elements with reference to a plane at right angles to the above mentioned plane.

The invention is also concerned with certain improvements in the means located on 60 the trailer or semi-trailer whereby the motion of the piston rod or the like on the truck or tractor is reproduced to tilt the trailer body.

The invention also consists in a six wheel 65 vehicle comprising a tractor and a semi-trailer together with a hydraulic hoist mounted on the tractor, cable means leading from the tractor to the semi-trailer and means on the latter actuated by the cable 70 means for tilting the body of the semi-trailer; also in means whereby the hoist may be utilized to lift the semi-trailer free and clear from the pivot mechanism by which it is normally connected to the tractor. 75

The invention further consists in certain features of construction shown, described and claimed.

In the drawings, Fig. 1 is a side view showing a preferred embodiment of the invention. Fig. 2 is a plan view corresponding thereto, parts being broken away and the trailer body being omitted. Fig. 3 is a section on about the line 3—3 of Fig. 1, showing the general arrangement of the 80 pump and associated parts, which, for sake of clearness, are omitted in Figs. 1 and 2. Fig. 4 is a similar enlarged fragmentary view of the upper end portion of the unit. Figs 5 and 6 are a side view and a plan view, 90 respectively corresponding to Fig. 4. Figs. 7 and 8 are fragmentary views corresponding to Figs. 4 and 5 and showing a modification wherein the different connections are independently made. Fig. 9 is an enlarged 95 fragmentary front view of the hoisting mechanism on the trailer. Fig. 10 is a side view corresponding thereto, parts being broken away. Fig. 11 is a section on the line 11—11 of Fig. 10, the sheave guard 100 being removed. Fig. 12 is a fragmentary plan view showing the spacer bar for hold-

ing the trailer spaced from the truck, the draw bar being omitted. Fig. 13 is a side view showing the application of the mechanism which appears in Figs. 9, 10 and 11 to a two-wheeled trailer. Fig. 14 shows the manner of lifting the trailer frame from the pulling vehicle.

The truck, as indicated in Fig. 1, includes the frame 1, the body 2 tilttable thereon about the pivots 3, and the upstanding hydraulic cylinder 4 which contains a piston, not shown, and has the piston rod 6 projecting therefrom. A pump 8, driven from the propelling engine 9, as by the shaft 10 and chain 11, Fig. 3, draws oil through the suction pipe 12 from the expansion chamber 13 and upper end of the cylinder and expels it through the pressure pipe 14 back into the cylinder below the piston, thus causing the latter to rise. The piston rod 6 is provided with a cross arm or head 16. The construction thus far described is well known as is the association therewith of a pair of pulleys 18, cables 19, equalizing bar 20, anchor strap 21 and body arms 22 whereby the piston rod tilts the truck body. However, the pulleys have heretofore in practice been permanently attached to the cross arm, whereas in the present instance 30 they are readily detachable therefrom as pointed out later.

Supported on the expansion tank or the upper end of the cylinder in any suitable way as, for example, by means of the guide flanges 30-31 with which the tank or the cylinder head 32 may be provided, are a pair of plates 35 which may be slid forward and back under the cross arm or head. These plates 35 are joined at their front and rear ends to form a chair or support by bolts 36 that pass through tubular spacers 38. Any suitable means, for instance, a spring pressed plunger 39, Fig. 5, adapted to be received in either of the holes 40 in one of the plates 35, serves to retain the support at one limit or the other of its movement against accidental displacement but permits it to be shifted easily by a driver grasping the front spacer 38 and pulling forwardly or pushing backwardly thereon as the case may be. I am aware, as suggested above, that the plates may be supported for movement relative to the piston rod in various ways other than that shown. 55 The plates are preferably each provided in their upper surfaces with a front notch 42 and a rear notch 43.

Arranged to be received in the notches 42 is a cross bar 44 the central portion of which 60 is curved to clear the piston rod (Fig. 6) and the ends of which are preferably welded in slots in the hooks or hook bars 45 to the lower ends of which cables 46 are attached. The lower surface of the cross bar 44 is inclined between the plates 35 as in-

dicated at 48, Fig. 4, from which it follows that the hook bars are normally maintained symmetrically disposed with reference to the longitudinal central vertical plane of the cylinder; and the position of the notches 42 70 is such that the hooks 45' at the upper ends of the bars 45 are centrally above the cross arm 16 when the chair is at its rearward limit of movement whereas, when the chair is at its limit of movement forwardly (Fig. 75 5), the hooks 45' are out of the path of the cross arm.

In like manner, the pivot pins 50 of the pulleys 18 are hung in straps 51 that are themselves pivoted at 52 to hooks 53, and the latter are joined by a cross bar 54 which is, except in matter of length, the counter part of the cross bar 44. The bar 54, as will be readily understood, is adapted to rest in the notches 43; when in the position shown in Fig. 5, the hooks 53 are in the path of the cross arm and will be picked up or caught and elevated thereby; however, when the chair is at the limit of its movement rearwardly, they are out of the way. Were 90 no means provided to prevent it, the weight of the pulleys and associated parts would tend to swing the hooks 53 counterclockwise (Fig. 5) in the notches 43 back into the path of the cross arm—the hooks are 95 therefore provided with lugs 55 that lie in the planes of the straps 51 below the center lines of the pins 52. The same thing may be accomplished in other ways, for example, the straps may be made integral 100 with the hooks, but the construction shown is preferred since it lends itself readily to commercial processes of manufacture.

To repeat:—When the parts are in the position shown (Fig. 5), the hooks 53 will 105 be caught by the rising cross arm and the truck body tilted, whereas when the chair is shifted backwardly the hooks 45-45' will in turn be lifted. The reverse arrangement would be less desirable since the hooks 45 110 might be in the way of the rising truck body. Moreover, the jarring of the vehicle, acting through the surfaces 48 and the upper surfaces of the notches 42-43, automatically tends to center both sets of hooks 115 properly with reference to the vertical longitudinal plane of the vehicle which includes the center line of the piston.

It is evident that the hooks 45-45' might be replaced by a second pair of hooks and 120 pulleys the counterpart of the elements 18-53 and that the latter might likewise be replaced by a second pair of hooks 45-45'. In any event, the chair is held in one of its limiting positions and gravity maintains the pairs of hooks always properly positioned, both longitudinally and transversely, on the chair so that the stresses in the piston rod are minimized and, for the most part, in direct compression.

As indicated in Figs. 7 and 8, the two sets of hooks may be independently operated by using in lieu of each plate 35 a pair of plates 35' and 35'', and by cutting away the 5 upper rear portions of the former and the upper front portions of the latter at 56 and 57, respectively, to provide clearance for the hook cross bars when the latter are resting in the notches 42' and 43'. Two retaining elements 39'-40' which may be the same in construction as the parts 39-40, are of course, provided. The piston rod may thus be made to simultaneously pull both sets of cables, or may be freed from both, and used 10 for other purposes if desired, or may be used to actuate either set at will. It will also be understood that in some instances it may be necessary to employ but one shiftable set, the other cables being actuated whenever the 15 piston rod is projected.

In the embodiment of the invention shown in Figs. 1 and 2, the cables 46 pass down through pulleys 60 on the base 61 of the hoist and thence rearwardly to the four 20 wheeled trailer. While the means for utilizing the cables to tilt the trailer body 62 about the pivots 63 on the frame 64 is subject to wide variation, it is preferred to employ the mechanism shown, since it not 25 only provides for low clearance and high tilting but also requires very few accurate machining operations. This mechanism includes a base 65 mounted on cross bars 66 and having threaded therein an upstanding 30 pipe 68 which is, in turn, threaded into a head 69 that includes in its front portion the ears 70 between which the shaft 71 of the double pulley 72 is mounted. At the 35 rear the head is provided with a roller 73 mounted on the shaft 74 that is carried in ears 75 joined and braced by the web 76. These parts, which may be manufactured 40 with very little machine work, constitute a guide that is preferably braced by the laterally and forwardly diverging tension rods 78 which preferably extend to the outer ends 45 of the front cross bar 66.

Reciprocable in the guide is a thrust bar 80, preferably formed of a pressed metal 50 channel having its web cut away at its lower end at 80' to allow clearance for the spherically faced roller 81 that turns on a shaft 82 bearing in the flanges of the thrust bar. The diameter of the roller is slightly less 55 than the inner diameter of pipe 68. Just above the roller is a cross pin 83 to which the cable 84 that is detachably connected to the cables 46 in any suitable way—say at the point 85, this connection being omitted 60 in Fig. 2—is anchored, for example, by forming it in a single run and looping it about the pin. In the embodiment shown both strands of the cable 84 pass around a double pulley 86 which is pivotally secured 65 to the base 65 by the links 87 and pins

88-89; and the cable is prevented from leaving the pulley 72 by means of a guard which is formed of a transverse strap 120 mounted on the ears 70 and riveted or welded at 121 to the circumferentially extending 70 element 122. The upper end portion of the thrust bar bears at its rear side on the roller 73 or at its front side (of the web portion) on the face of the pulley 72, depending on which way it may tend to swing, thus minimizing friction and at the same time bracing the thrust bar at a point substantially at the top of the guide. The clearance between the roller 73, the pulley 72, and the thrust bar being small, and the distance from the 80 roller shaft 82 to the shaft 74 being relatively great, even when the thrust bar is in its uppermost position, the motion of the thrust bar is substantially rectilinear.

The connection between the thrust bar and 85 the body may be varied: as shown, it comprises a cross arm 90, pulleys 91, cables 92, equalizer 93, anchor strap 94 and body arms 95, which may be duplicates, respectively, of the parts 16, 18, 19, 20, 21 and 22 heretofore described.

For the purpose of relieving the drawbar 96 of thrust when the trailer body is being dumped, the rear cross bar of the truck frame and the front cross bar of the trailer 95 frame may be provided with brackets 97 and 98 between which the spacer bar 99 of any suitable construction, say a pipe section, is supported at such times—see Fig. 12. The draw bar might, of course, be of the thrust 100 receiving type, as shown and claimed in my above identified applications.

Certain features of the invention are applicable advantageously to that type of trailer known as the "semi-trailer"—Figs. 105 13 and 14. In this case, the cylinder 4, piston rod 6, together with the associated pump and related mechanism (not shown, but preferably the same as heretofore described) are carried on the tractor frame 100. The 110 hooks 101 alone are used and the cables 102 that correspond to the cables 46, lead rearwardly through pulleys 103, which correspond to the pulleys 60, to certain mechanism indicated as a whole by 105 and corresponding in construction to those parts previously described as positioned on the four wheel trailer, whereby the body 108 may be tilted about the pivots 109 as before. It is desirable that the mechanism 105 be positioned with the axis of the tubing or pipe 115 substantially in alignment with that of the fifth wheel or pivot 110 thus minimizing the tendency to tension the cables 102 as the trailer swings. By providing a little slack 120 in the cables, all necessary relative movements may be permitted.

By disconnecting the cables 102 (which may be accomplished by disconnecting the pulleys 103, or in any other preferred man-

ner) and connecting cables 111 between the cross bar 16 and a suitable anchorage or anchorages 112 on the front end of the trailer frame 114, the latter may be elevated as shown in Fig. 14 to allow the insertion of a suitable support (not shown), so that either one of a plurality of the trailers may be used with a single pulling vehicle as in common practice with such vehicles.

10 One main advantage in mounting the hoisting cylinder on the tractor, as distinguished from semi-trailer constructions heretofore used wherein the cylinder is mounted on the semi-trailer frame, resides 15 in the ease with which the connections between the pump and the cylinder may be maintained, it being understood that the pressures are necessarily so high as to make it a matter of great difficulty to prevent leakage when the cylinder is on the trailer frame 20 and the pump on the tractor. The present construction is also advantageous over installations in which both pump and cylinder might be mounted on the trailer frame, 25 since it would then be difficult, if not impractical to drive the pump from the propelling engine.

It is evident that the construction of the hook attaching and detaching mechanism 30 may be modified within wide limits without departing from the spirit of the invention; and it is again pointed out that this mechanism may be used for many purposes additional to or other than the tilting of trailer bodies, such, for example, as the hoisting or dragging of loads into the vehicle, or the operation of loading skips external to the vehicle and the like. The invention is also applicable to horizontal cylinders and cable hauling mechanism as well as to the vertical or upright type. I do not, therefore, wish to be limited except as indicated by the subjoined claims.

1. In mechanism of the class described, a 45 guide, a member reciprocable therein, supporting means, a pulling element adapted to be actuated by the reciprocable member and also adapted to rest on the supporting means, said supporting means being shiftable to 50 connect the pulling element to the reciprocable member and to disconnect it therefrom at will.

2. In combination, a reciprocable bar having a cross head or arm, a pair of connected 55 hook-like elements adapted to co-act with and be actuated by the cross head or arm at points substantially equally distant from the center line of the bar, a movable support for said elements whereby they may be shifted 60 into the path of the cross head or arm or may be removed therefrom at will.

3. Cable hauling mechanism comprising a reciprocable bar, a hook-like element, a movable transfer support for the element so constructed and arranged that the latter may be

supported thereby and moved into or from the path of the bar at will.

4. Pick-up mechanism for cable hauling means comprising a reciprocable bar, a hook-like element to be actuated thereby, means 70 such as a chair, upon which the element is adapted to rest, said means being movable to carry the element into the path of the bar at will, and said bar being arranged to thereafter remove the element from the 75 means on which it is adapted to rest.

5. In mechanism of the class described, a reciprocable member, a hook or the like adapted to be actuated thereby, and means for normally supporting the hook and for 80 properly centering it with reference to the line of travel of the reciprocable member, said means being movable to remove the hook from the path of the reciprocable member at will.

6. A reciprocable member, a guide in which the member travels, a pair of hooks adapted to be moved into and from the path of travel of the member, and means for selectively moving the hooks into and from 90 said path.

7. In mechanism of the class described, a guide, a member reciprocable therein, supporting means, pulling elements adapted to be actuated by the reciprocable member and 95 also adapted to rest on the supporting means, said supporting means being shiftable to carry either of the pulling elements into the path of the reciprocable member at will.

8. A vehicle comprising an upstanding cylinder, a piston rod reciprocable therein and projecting from the upper end thereof, a pulling element adapted to be actuated by the piston rod, and a shiftable support for 105 the pulling element whereby said element may be operably connected to or disconnected from the piston rod at will.

9. A vehicle comprising an upstanding guide, a member reciprocable therein and 110 projecting from the upper end thereof, a pulling element adapted to be actuated by the member, and means carried by the upper end portion of the guide for automatically disconnecting said element from the member as the latter approaches the limit of its 115 downward movement.

10. A vehicle comprising a guide, a member reciprocable therein, cable mechanism adapted to be actuated by the member, and means for automatically disconnecting said cable mechanism from the member as the latter approaches the limit of its movement in one direction, said means being shiftable to thereafter maintain the cable mechanism 125 disconnected from the member.

11. In combination, a reciprocable member including a cross head or arm, a pair of pulling elements adapted to be simultaneously caught and carried along by the cross 130

- head or arm, a chair or support upon which the pulling elements are normally supported, the parts being so constructed and arranged that vibration or jarring tends to maintain
- 5 the pulling elements equally spaced from the center line of the reciprocable member.
12. In combination, a reciprocable member, guides extending transversely of the member on opposite sides thereof, a chair
- 10 slideable in said guides, the upper surface of the chair being notched, a cross bar arranged to normally rest in the notch when the reciprocable member is at one point in its movement, a pair of hooks one secured
- 15 to each end of the cross bar, said hooks being arranged in the path of the reciprocable member when the chair is in one position and being removed from the path of the reciprocable member when the chair is in
- 20 another position.
13. In combination, a reciprocable member, guides extending transversely of the member on opposite sides thereof, a chair slideable in said guides, a cross bar arranged
- 25 to bear on said chair at two points spaced from one another and carrying a pair of hooks one near each end, said cross bar being shaped to co-operate with the chair to automatically space the hooks equally from
- 30 a longitudinal central plane through the reciprocable member, whereby when the chair is shifted the hooks are caught up by the reciprocable member and twisting stresses in the latter are substantially eliminated.
- 35 14. A vehicle comprising a frame, a body tiltable about a horizontal axis near the rear end thereof, an upstanding guide forwardly of the body, a member reciprocable in said guide, a pair of pulleys adapted to be actuated by said member, cable means passing over said pulleys and connected to the front end portion of the body whereby the body is tilted when the reciprocable member is projected, hook-like elements whereby the
- 40 sheaves are supported, and means for supporting the hook-like elements independently of the reciprocable member when the latter is in lowered position, said last named means being shiftable to carry the hook-like elements into the path of the reciprocable member and remove them therefrom at will.
- 45 15. In combination with a tiltable receptacle, an upstanding guide adjacent thereto, a member reciprocable therein, means adapted to be actuated by the member for tilting the receptacle, said means including a pair of shiftable elements adapted to be moved into or from the path of the member, and means carried by the upper end portion of
- 50 the guide for thus moving said elements at will.
- 55 16. A vehicle comprising a body tiltable about a horizontal axis near the rear end of said vehicle, an upstanding guide forwardly of the body, a member reciprocable in the
- guide, cable means adapted to be actuated by the reciprocable member for tilting the body, and means carried by the guide and operable from the front side thereof for connecting the cable means to the reciprocable member or disconnecting it therefrom at will when the body is in lowered position.
17. In combination, a pulling vehicle including a propelling engine and a cable hauling mechanism driven by said engine, a trailer having a tiltable body joined to the pulling vehicle by a draw bar connection, means on the trailer and actuated by the cable hauling mechanism for tilting the body at will, and a detachable thrust bar, independent of the draw bar connection, for spacing the vehicles apart when the body is being tilted.
18. Hoisting mechanism comprising a guide, a member reciprocable therein, a pulling element drawn in one direction by said member and tending to draw said member in the opposite direction, and means for automatically disconnecting said element from said member as the latter approaches the limit of its movement in said opposite direction.
19. In combination, supporting means, a reciprocable member, a pair of pulling elements normally carried by said support and adapted to be drawn by said member in one direction from said supporting means, said elements being automatically centered on said supporting means with reference to the line of travel of said member.
20. Pick-up mechanism for a pair of spaced pulling elements comprising a reciprocable member, and supporting means for said elements on which they are loosely carried and on which they are automatically centered with reference to the line of travel of said member by their own weight.
21. In combination, a hook, a reciprocable member adapted to fit into said hook and to elevate the latter, and laterally shiftable means normally supporting said hook with its curved portion sufficiently above said member to permit said hook being shifted by said means into or from the path of said member at will.
22. In combination with a tiltable receptacle, an upstanding guide adjacent thereto, a member reciprocable therein and including a cross-arm, and means actuated thereby for tilting said receptacle, said means including a pair of pulling elements one for each end of said cross-arm, and movable supporting means for said elements arranged to simultaneously move said elements into or from the path of said cross-arm at will.
23. Cable hauling mechanism comprising a reciprocable member, pairs of pulling elements adapted to be moved into and from the path of travel of said member so as to

thereafter be carried along by said member, said elements, and shiftable supporting means for selectively moving said pairs of elements into and from said path.

24. Pick-up mechanism for a pair of spaced pulling elements, comprising a reciprocating member adapted to carry said elements in one direction, means connecting

means for said connecting means constructed and arranged to present said elements in 10 the path of travel of said member at substantially equal distances from the center line thereof.

LOUIS M. SPENCER.
